UNITED STATES PATENT OFFICE

163,515

HOUSEBOAT

Clyde E. Gray, Hot Springs, Ark.

Application June 30, 1949, Serial No. 3,636

Term of patent 3½ years

(Cl. D71—1)

To all whom it may concern:

Be it known that I, Clyde E. Gray, a citizen of the United States, residing at Hot Springs, in the county of Garland, and State of Arkansas, have invented a new, original, and ornamental Design for House Boat, of which the following is a specification, reference being had to the accompanying drawings forming a part thereof.

In the drawings:

Fig. 1 is a perspective view of my house boat showing my new design and looking toward the left side and rear;

Figs. 2 and 3 are side elevational views;

Fig. 4 is a plan view; and

Fig. 5 is an end view looking toward the front end of the boat.

I claim:

The ornamental design for a house boat, substantially as shown.

CLYDE E. GRAY.
